UNITED STATES PATENT OFFICE.

TOM YEN FOOK, OF MESA, ARIZONA.

SPRING-HINGE.

1,312,392.

Specification of Letters Patent. Patented Aug. 5, 1919.

Application filed June 26, 1918. Serial No. 241,971.

To all whom it may concern:

Be it known that I, TOM YEN FOOK, a citizen of the United States, residing at Mesa, in the county of Maricopa and State of Arizona, have invented certain new and useful Improvements in Spring-Hinges, of which the following is a specification.

This invention relates to improvements in spring hinges.

10 The object of the invention is to provide spring hinges of the type known on the market as "The King" and others with simple and efficient means for securing them to the door and its jamb in connection with which 15 the hinge is to be used to insure their retention in operative position.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within 25 the scope of what is claimed without departing from the spirit of the invention.

In the accompanying drawings:—

Figure 1 represents a front elevation of a portion of a door and its jamb with a hinge embodying this invention shown applied,

30 Fig. 2 is a horizontal section taken on the line 2—2 of Fig. 1,

Fig. 3 is a detail perspective view of one member of the hinge, and

35 Fig. 4 is a similar view of a portion of the other member.

In the embodiment illustrated, the hinge constituting the invention is shown applied to a door D and its jamb J and comprises 40 two plates 1 and 2 connected by a pintle 13 presently to be described, and having smooth apertures for securing them respectively to the jamb and to the door.

The plate 1 has apertured ears 4 extending 45 from the edges of its opposite ends in the same direction at right angles to the plate, which are designed to receive the pintle which connects the two plates. A spring barrel or cover 3 is carried by the edge of 50 plate 1 intermediate its ends on which the pintle receiving ears are mounted, and an attaching plate 5 extends laterally at right angles from the edge carrying the barrel 3 in a direction opposite to said barrel, and which

is apertured as shown at 6 to receive screws 55 6' which fasten it to the door jamb, as shown in Fig. 2.

The plate 2 has spring barrels 8 and 9 at one side edge near its upper and lower ends, and which are designed to aline with the 60 barrel 3 when the hinge members are assembled in operative position. Between the barrels 8 and 9 is a right-angularly extending apertured attaching plate 10 which is designed to fit flat against the edge of the door 65 D, the apertures 11 being designed to receive the fastening screws.

In the application of this hinge, the plate 1 is secured to the door jamb by screws passing in planes at right angles through the 70 body portion and plate 5, respectively, said plate 5 being engaged with the edge of the jamb, and the body portion of plate 1 with its outer face. When in this position the pintle receiving ears 4 and the barrel 3 extend beyond the outer face of plate 1 in the position shown in Figs. 1 and 2. The plate 2 is then secured to the door D in a similar manner, plate 10 lying against the edge of the door which is to be hinged, and plate 2 75 against its outer face, so that the fastening screws which attach plates 1 and 10 to the door extend in planes at right angles to each other, and thereby securely hold the plate engaged with the door. The door is then 80 placed in position with the barrels 8 and 9 of its hinge member 2 alined with the barrel 3 of the jamb carrying hinge member 1. When these parts are so positioned the apertured ears 7 of plate 2 lap the ears 4 of plate 85 1 and the pintle 13 is passed through the apertures therein, this connecting the door hingedly to the jamb, and preventing all danger of the hinge members becoming detached.

90 A coiled spring 12 is mounted in the registering barrels 8, 3 and 9 with its ends secured so that the spring will exert its tension to normally close the door.

95 The foregoing description and the drawings have reference to what may be considered the preferred or approved form of my invention. It is to be understood that I may make such changes in construction and arrangement and combination of parts, materials, dimensions, etc., as may prove expedient and fall within the scope of the 100 105 claimed invention.

Having thus fully described my invention, what I claim as new and desire to secure by Letters Patent, is:—

A hinge of the class described comprising 5 hinged leaves apertured to receive fastening screws, pintle receiving ears extending in the same direction substantially at right angles from their end edges, the ears of one leaf adapted to lap those of the other when 10 in operative position, the overlapping ears flaring slightly toward their free ends, one of said leaves having an attaching plate extending at right angles from one side edge thereof near one end, and in a direction opposed to said ears and apertured to receive 15 attaching screws, a spring barrel on the op-

posite face of said leaf spaced from the end thereof, the other leaf having an attaching plate at one edge midway its ends, the attaching plates of the two leaves being located in vertical planes one above the other when the members are assembled, and spring barrels arranged adjacent each end of the second mentioned leaf member, the barrels of the two leaves alining when the parts are 20 25 assembled.

In testimony whereof I affix my signature in presence of two witnesses.

TOM YEN FOOK.
